UNITED STATES PATENT OFFICE

PERCY W. VALENTINE, OF NATICK, MASSACHUSETTS

METHOD AND APPARATUS FOR LASTING AND ROUGH ROUNDING STITCH-DOWN SHOES

Application filed November 16, 1928. Serial No. 319,898.

The present invention relates to the art of shoe making and is particularly concerned with the step of pulling the upper around the last and stitching the outturned upper 5 to an inner or intermediate sole. Its object is to combine with the lasting and stitching step, a further step which has heretofore always been performed separately at a later stage in the making of the shoe; that is, the 10 step of rough rounding the sole and trimming the edges of the upper wherever they extend beyond the intended outlines of the rough rounded sole.

Heretofore in the making of stitch-down 15 shoes, the practice has been to rough round or trim the sole after the upper has been lasted and stitched to the sole. In cases where the shoe is made with both an inner and an outer sole, or inner, middle and outer 20 soles, the practice has been to defer the rough rounding or trimming step until the outer sole has been secured to the shoe, then to rough round all the soles and trim the upper in one operation and afterwards shave 25 the sole to its final finished dimensions.

In carrying out my present object, I make use of a machine having means for both pulling down the upper around the last and stitching it to the innersole, and provide the 30 machine with a knife situated at such a distance from the awl or needle of the machine and in such a location that it cuts off the outstanding edges of the innersole and upper while the connecting seam is being sewed. 35 The invention consists both in the combined operation of lasting, stitching and rough rounding, and in the means by which such operation is performed, said means comprising the combination of a presser or puller, 40 a stitch forming means or a piercing tool, and a knife or cutter, substantially as hereinafter described and pointed out in the appended claims.

In the drawings illustrating the invention, 45

Fig. 1 is a fragmentary elevation of so much of a lasting and sewing machine equipped with a trimmer in accordance with my invention as is necessary to illustrate the 50 invention;

Fig. 2 is a fragmentary sectional view on a larger scale of the parts which directly cooperate with the shoe;

Fig. 3 is a similar view showing the operating parts in different positions; 55

Fig. 4 is a perspective view of the same parts, omitting the needle;

Fig. 5 is a view similar to Fig. 2 showing a slight modification in the form of the work support and lasting presser; 60

Fig. 6 is an elevation of the parts shown in Fig. 5, as viewed from the left of said figure; the line 5-5 on Fig. 6 indicating the plane on which the section shown in Fig. 5 is taken; 65

Fig. 7 is a perspective view of a fragment of a stitch-down shoe illustrating the result of my new process and apparatus.

Like reference characters designate the 70 same parts in all the figures.

The particular embodiment of the invention herein illustrated has been applied to a sewing machine of known character, wherefore I have shown only the instruments and parts which directly engage and act on the 75 shoe, omitting illustration and description of the mechanisms by which these parts are operated in their proper sequence. The information of those skilled in the art of sewing machine construction and use is sufficient 80 to enable such persons to perform, construct and use the present invention from the description and illustration herein furnished.

In Fig. 1, the part 11 designates an upright rising from the base of the sewing 85 machine on which is mounted a work support 12 and in which there is a guide 13 for a needle bar 14 carrying a needle 15. 16 is an overhanging arm carrying a head 17 in which is reciprocatively mounted an awl bar 18 90 carrying an awl 19, and the shank 20 of a presser 21. The particular machine thus illustrated is one which forms a chain stitch seam from a single thread. The awl pierces the work, the needle rises through the holes so pierced, receiving the thread in its hook and pulling it through the work, and the work is fed in a known manner. Other instruments, not shown because unnecessary for the 95 information of those skilled in the art, form 100

the loops in the thread necessary to secure the stitches, and tighten the stitches.

The work, a shoe to be lasted, comprises a last 22, to the bottom of which an innersole 23 has been temporarily attached, and over which a shoe upper 24 has been placed. It is applied to the work support with the bottom of the innersole bearing on the serrated inclined surface 25 of the latter, and the flange 23a of the innersole and outturned edge 24a of the upper overlying the top of the work support and extending across the passage 26 in the latter through which the awl and needle are adapted to pass. The presser 21 is advanced toward the work support and in doing so it engages the edge part of the upper, pressing this part against the flange of the sole and pulling the upper around the last and tucking it into the angle between the side of the last and the projecting flange of the upper. By arranging the surface 25 of the work support at an inclination, the presser is enabled to pull the upper closely around the last and into the angle.

While the presser clamps the upper and innersole against the work support, as shown in Fig. 3, the awl advances into the passage 26 and withdraws, and the needle advances and withdraws in turn, forming the stitch.

A knife 27 is secured by a clamp 28 to the awl bar beside the awl. Such knife has a wide end with a cutting edge, its width at the end being at least as great as the feed of the work between stitches, so that the cuts which it makes on successive advances are joined together. It advances with the awl and passes into an opening or passageway 29 in the top of the work support, cutting off those parts of the sole and upper which extend across its path. Its distance from the awl is equal to the greatest width of the designed extension of the sole beyond the stitches of the attaching seam.

It will be apparent from the foregoing description that, as the upper is pulled about the last and stitched to the innersole, the extension edges of both the sole and the upper are trimmed off, the successive incisions of the knife making a continuous cut which severs the surplus material, as indicated by Fig. 7, which shows the cut at 30 and the severed scrap at 31. Thus the shoe is trimmed or rough rounded throughout the full extent of the attaching seam. In some styles of shoe, the lasting, trimming and rounding are carried out around the heel part as well as the fore part, while in others this operation extends around the shank and fore part only, the edges of the upper at the heel part being turned in under the heel seat. In both cases, however, the combined operation as carried out according to this invention is the same.

In Figs. 1-4 inclusive the top surface of the work support is shown as being horizontal,

that is, perpendicular to the paths in which the awl and rounding knife travel. With this arrangement the trimmed edges are square with the bottom of the innersole. It is not essential, however, that the edges should be trimmed off square, particularly in the case of shoes having innersoles made of thin stock. In such cases the top of the work support may be inclined, as shown in Figs. 5 and 6, either at the same angle as the face 25 or at a different angle, the presser 21a being similarly inclined.

After completion of the step just described, an outer sole is applied to the bottom of the lasted shoe and the shoe is then completed in the ordinary way, or otherwise as desired; with this important exception, however, that the usual step of rough rounding after applying the outer sole is omitted.

The invention thus described is useful and valuable by reason of effecting important savings as follows:

First, it eliminates the step of rough rounding as a separate operation, thus saving the cost of rough rounding machines and of their maintenance, and saving the time and expense of performing this operation.

Second, it enables the outer soles to be cut more nearly than heretofore to finished size, since they may be made of approximately the form and dimensions of the trimmed innersole without the excess width and length heretofore provided. Thus the waste of outer sole stock incident to rough rounding is eliminated and more soles may be cut from a side of leather. The outer soles require only finish shaving or trimming to final form and dimensions, with the waste of only a small amount of stock thereby.

It is to be understood that the description hereinbefore given of a particular type of sewing machine as the basis of an apparatus for carrying out my invention is not intended as a limitation of the invention to a machine of that type only. On the contrary, the method and means of lasting, stitching and rough rounding here described may be carried out in connection with machines adapted to form stitches by other means and of other types than the chain type.

In this specification the term "innersole" is intended to include not only a single innersole but both an inner and an intermediate sole, where such is used, and is stitched with the innersole to the upper. That is, this term includes all the soles other than the outersole which may be united to the upper independently of the outersole.

What I claim and desire to secure by Letters Patent is:

1. The method of shoe making which consists in lasting an outturned upper and stitching an innersole thereto with simultaneous rough rounding of the innersole.

2. In the manufacture of stitch-down shoes, simultaneously lasting a shoe, stitching the upper and innersole together and trimming the innersole to rough rounded dimensions. 70
- 5 3. In the manufacture of stitch-down shoes, simultaneously lasting the upper, stitching an innersole thereto and trimming the innersole, and subsequently applying an outer sole having substantially the same dimensions as the innersole thus trimmed. 75
- 10 4. In the manufacture of stitch-down shoes, the method which consists in placing an innersole on the bottom of the last with extension edges protruding from the edges of the last bottom, pulling an upper over the last, and tucking the upper into the angle between the side of the last and the sole extension in such manner that the edge part of the upper is turned outward, and at the same time stitching the outturned upper and innersole extension together and trimming the edge parts of the upper and innersole to substantially rough rounded dimensions. 80
- 15 5. In the manufacture of stitch-down shoes, the method which consists in applying an innersole to the bottom of a last with its edges extending beyond the edges of the last bottom, placing an upper over the last, progressively tucking the upper along a line thereof inward from its edge into the angle between the side of the last and the extension of the innersole, throughout the circuit of at least the forepart of the shoe, so that the edge portion of the upper is thereby laid against the innersole extension, and simultaneously and progressively stitching the extensions of the upper and innersole together and trimming off the edges of such extensions to substantially rough rounded dimensions. 85
- 20 30 6. A machine for lasting, stitching and trimming stitch-down shoes comprising pressing, piercing and stitch forming instrumentalities, and a cutter connected to one of said instrumentalities for cutting off the outstanding edge of the innersole during the lasting and stitching operation. 90
- 35 40 7. An apparatus for use in the performance of the within described method comprising a work support adapted to support the sole, including the marginal portion thereof, of a shoe in process of being lasted, pressing means movable toward and away from said work support in position to press the upper of a shoe into the angle between the side of a last and the margin of the sole, stitch forming means arranged to form stitches uniting the marginal part of the sole to the outturned margin of the upper, and a cutter arranged to operate between the boundaries of said work support for trimming the sole to rough rounded dimensions. 95
- 45 50 8. A machine for lasting, stitching and rough rounding the sole of a stitch-down shoe, comprising a lasting presser arranged and operable to tuck the upper into the angle be- 100
